UNITED STATES PATENT OFFICE

MICHAEL F. BROGAN, OF LAWRENCE, MASSACHUSETTS, ASSIGNOR TO UNITED SHOE MACHINERY CORPORATION, OF PATERSON, NEW JERSEY, A CORPORATION OF NEW JERSEY

METHOD OF AND DEVICE FOR STOCK FITTING

Application filed August 10, 1926. Serial No. 128,400.

This invention relates to stock fitting devices and to improvements in the art of stock fitting. As herein illustrated the invention is particularly concerned with the fitting of out-
5 soles for use in making McKay sewed shoes.

In the manufacture of McKay sewed shoes it is customary to prepare the outsole for attachment to the upper by forming a channel and a channel flap in the tread face side
10 of the sole and cutting into the sole material beneath the channel flap to form a groove to receive the sole attaching stitches. While the results obtained by the practice of this method are generally satisfactory it sometimes
15 happens, particularly when thin soles are being operated upon, that the cutting of the stitch-receiving groove disadvantageously weakens the sole in the region through which the stitches are to pass.
20 In view of the foregoing, one object of the present invention is to avoid danger of weakening a sole as a result of the formation of a stitch-receiving groove therein.

With this object in view, one feature of the
25 invention consists in the provision of a knife for cutting a piece of stock, and means on the knife for pressing a groove in the surface cut by the knife. As herein shown, the groove forming means is designed particularly to form a stitch-receiving groove within the channel of a shoe sole and to this end it comprises a small projection formed on a channel knife of a type customarily employed in
30 sole channeling machines, said projection being constructed and arranged for indenting or pressing the groove in the channeled portion of the sole beneath the channel flap. In the illustrated machine, the channeling and
35 grooving are caused to proceed progressively along the margin of the sole by means constructed and arranged to support the sole unyieldingly and to feed it continuously past the channel knife. The illustrated groove-forming projection is formed on the lower
40 face of the channel knife just behind the cutting edge and is adapted to form the groove without weakening the sole by the removal of material therefrom but, on the contrary as
45 above indicated, by compressing or consolidating the material and compacting the fibres
50

thereof in the immediate vicinity of the wall of the groove.

Preferably, although not necessarily, the opposite sides of the groove forming projection are tapered or beveled both forwardly 55 toward the cutting edge of the knife and downwardly from the lower face of the knife so that the forward portion of the projection somewhat closely resembles the bow of a boat in shape, having a more or less sharply defined ridge for initiating the pressing or indenting action of the projection. Thus the projection is enabled the more readily to embed itself in the sole material and to apply
60 a rubbing groove-forming pressure thereto. 65

In another aspect the invention provides an improved method of grooving shoe soles which consists in operating progressively along the margin of a sole to form a channel and a channel flap, and simultaneously grooving the margin of the sole beneath the channel flap without removing material therefrom. 70

Invention is also to be recognized in the provision of a new article of manufacture 75 comprising a shoe sole having a marginal groove at one side, a flat surface opposite the groove at the opposite side of the sole, and a region between the groove and said flat surface in which the sole material is abnormally compacted or consolidated. 80

The invention will be explained with reference to the accompanying drawing, in which

Fig. 1 is a fragmentary view, partially in side elevation and partially in section, of a channeling machine embodying the present invention and illustrating the operation of the machine upon a sole; 85

Fig. 2 is a detailed view in side elevation and on an enlarged scale of a portion of the sole channeling and grooving device shown in Fig. 1; 90

Fig. 3 is a sectional view taken along the line III—III of Fig. 2; 95

Fig. 4 is a bottom plan view of the device shown in Fig. 2;

Fig. 5 is an end elevational view of the device; and Fig. 6 is a perspective view of a portion of a sole after the sole has been oper- 100

ated upon by the device shown in Figs. 2 to 5, inclusive.

Referring first to Fig. 1, the illustrated channeling machine, the operative parts of which are shown in said figure, is of the type disclosed in U. S. Letters Patent No. 1,004,614, granted Oct. 3, 1911, on application of H. W. Winter. The lower feed wheel of this machine is indicated at 6, the upper feed wheel at 8, and the edge gage roll at 10. These parts are constructed, arranged and operated as fully described in said patent. Secured to a channel knife holder 12 of the usual construction, by means of suitably arranged bolts 14, is a channel knife 16 of the drag cut type. As described in the Letters Patent above referred to the lower feed roll 6 is unyieldingly mounted while the upper feed roll, together with the channel knife carrier 12, is yieldingly 20 pressed toward the lower feed roll. The knife 16 is provided with the usual depending cutting blade 18 (Figs. 2-5). The blade 18 is shaped to provide a flat lower surface 19 and the blade is sharpened at one side to provide a horizontal cutting edge 20. The machine is adapted to operate upon a sole S, which, as illustrated, is to be fitted for use in a McKay sewed shoe, and the knife 16 is adapted to form a channel and a channel flap 25 such as indicated respectively at 22 and 24 in Fig. 6. Means is also provided on the knife 16 for forming a stitch-receiving groove 26 in the material beneath the channel flap 24.

For the purpose of forming the groove 26 in the sole without removing any material from the sole so as to weaken the sole, the knife 16 is made with an integral projection 28 upon the flat lower surface 19 of the knife blade. This projection or groove forming device 28 is located a short distance back of the cutting edge of the knife 16 and is spaced inwardly a short distance from the free extremity of the knife blade so as to locate the groove at the proper distance from the base or root of the channel flap. The projection 28 extends downwardly beyond the lower face 19 of the knife a distance equal to the depth of the groove which is to be formed in the sole. As best shown in Figs. 4 and 5 the opposite sides of the groove forming projection 28 are symmetrically disposed and they are inclined or beveled both downwardly from the face of the knife blade and forwardly toward the surface 19, the inclined faces of the projection meeting so as to form a more or less sharply defined ridge or forward edge 30 which slopes toward the knife blade and is adapted to initiate the indenting action. As a result of this formation of the projection 28 the forward end of the projection more or less closely resembles in shape the bow of a boat and the projection is thus particularly well adapted for pressing a groove in the sole as the knife 16 operates to cut a channel therein. The

projection functions to form the groove by an indenting or pressing action as distinguished from a cutting or gouging action. The lower feed roll supports the sole unyieldingly and in such a manner as to insure that notwithstanding the indenting action of the projection 28 the surface opposite the groove at the flesh side of the sole will be maintained flat and smooth even if the sole is very thin.

The above described manner of forming the groove has the advantage of abnormally compressing or compacting the stock in the region between the groove and the flat surface at the opposite side of the sole instead of weakening the sole by the removal of material therefrom. In fact, inasmuch as the material is compacted or consolidated in the vicinity of the groove by the action of the grooving device the sole may be actually strengthened or toughened in this locality so that additional resistance will be offered to strains tending to pull the sole attaching stitches through the material of the sole. Thus this mode of grooving a sole is particularly well adapted for use in connection with thin soles which might be unduly weakened by the cutting away of material in the process of forming the groove in accordance with methods heretofore practiced.

Having fully described my invention, what I claim as new and desire to secure by Letters Patent of the United States is:

1. In a sole fitting machine, in combination, a channel knife constructed and arranged to form a channel having one side defined by a plane surface in the body of the sole, and a grooving member shaped to operate upon said plane surface to make a stitch-receiving groove therein without removing material from the sole.

2. In a stock fitting machine, means for feeding a piece of stock, and a tool for simultaneously forming a channel in the stock and to produce by pressure a groove in a previously ungrooved portion of the channeled surface.

3. In a stock fitting machine, a knife for cutting a piece of stock, means for feeding the stock past the knife, and means on the knife for pressing a groove in the surface cut by the knife while the stock is being fed.

4. In a channeling machine, mechanism for feeding a shoe sole, and a tool for simultaneously forming a channel and pressing a stitch-receiving groove in the channeled portion of the sole as the sole is being fed.

5. In a sole channeling machine, in combination, a channel knife, and a groove-forming member constructed and arranged to mold the material adjacent to a channel cut in a sole by said knife to make a stitch-receiving groove of curvilinear cross-sectional contour in the body of the sole.

6. A stock fitting tool having means for

forming a channel in a piece of stock, and means constructed and arranged to press a groove in a previously ungrooved side of the channel.

5 7. A knife for cutting a piece of stock, and means on the knife for pressing a groove in the surface cut by the knife.

10 8. A channel knife for making a channel and a channel flap in a shoe sole, and a projection on the knife constructed and arranged to form by pressure a groove in the material beneath the channel flap, without removing material from the sole.

15 9. A channel knife for cutting a channel in a shoe sole, and a solid projection on the blade of the knife shaped to form a groove in the wall of the channel while the knife is cutting, said projection having tapering sides to facilitate the formation of the

20 groove.

25 10. A channel knife for cutting a channel in a shoe sole, and a projection on the blade of the knife shaped to form a groove in the wall of the channel while the knife is cutting, said projection having sides inclined both toward the cutting edge of the knife and downwardly from the lower face of the knife to facilitate the formation of the groove.

30 11. A channel knife for cutting a channel in a shoe sole, and a projection on the blade of the knife shaped to form a groove in the wall of the channel while the knife is cutting, said projection being shaped and arranged to provide a forward edge which slopes toward the knife blade to facilitate the forming of the channel.

35 12. That improvement in the art of fitting shoe soles which consists in operating progressively along the margin of a sole to form a channel and a channel flap, and forming solely by pressure a groove in the material beneath the channel flap during the progress of the channel forming operation.

40 45 13. That improvement in the art of fitting shoe soles which consists in operating progressively along the margin of a sole to form a channel and a channel flap, and simultaneously grooving the margin of the sole beneath the channel flap without removing material therefrom.

45 50 14. That improvement in the art of fitting shoe soles which consists in progressively forming a channel and a channel flap in a sole, and applying rubbing pressure to previously ungrooved material at one side of the channel to produce a stitch-receiving groove therein.

55 60 In testimony whereof I have signed my name to this specification.

MICHAEL F. BROGAN.
